(57) **CLAIM**

The ornamental design for a housing for a surveillance camera, as shown and described.

DESCRIPTION

FIG. 1 is a top, front and right side perspective view of a housing for a surveillance camera showing our new design; FIG. 2 is a bottom, rear perspective view thereof;

FIG. 3 is a front elevational view thereof;

FIG. 4 is rear elevational view thereof;

FIG. 5 is a left side elevational view thereof;

FIG. 6 is a top plan view thereof; and,

FIG. 7 is a bottom plan view thereof.

The portions of the article in broken lines are shown for illustrative purposes only and form no part of the claimed design.
